(57) **CLAIM**

The ornamental design for a butterfly on branch lighting ornament, as shown and described.

DESCRIPTION

FIG. 1 is a perspective view of a butterfly on branch lighting ornament showing my new design;

FIG. 2 is a front view thereof;

FIG. 3 is a top plan view thereof;

FIG. 4 is a left side view thereof;

FIG. 5 is a bottom view thereof; and,

FIG. 6 is a right side view thereof.

The broken line showing of the fastening element on the ornament is for environmental purposes only and forms no part of the claimed design.
